UNITED STATES PATENT OFFICE.

EDWARD V. ANDERSON, OF MONESSEN, PENNSYLVANIA, ASSIGNOR OF ONE-HALF TO
CHARLES E. GOLDEN, OF CRAFTON, PENNSYLVANIA.

AUTOMATIC FIRE-SERVICE VALVE.

1,189,335.

Specification of Letters Patent. Patented July 4, 1916.

Application filed May 5, 1915. Serial No. 26,070.

To all whom it may concern:

Be it known that I, EDWARD V. ANDERSON, a citizen of the United States, residing at Monessen, in the State of Pennsylvania, 5 have invented certain new and useful Improvements in Automatic Fire-Service Valves, of which the following is a specification.

My invention relates to valves employed 10 for automatically extinguishing fires, and its more particular objects are to provide means for maintaining a reduced pressure normally in the line, and at the same time provide for automatically and certainly 15 opening the line wide in case of fire.

Other objects are to simplify the construction and operation of fire service valves, to render more certain and generally improve the operation of such valves.

20 The invention is shown in several preferred forms in the accompanying drawings, wherein,—

Figure 1 is a central vertical section of the main valve with its operating devices. 25 Fig. 2 is a similar section of a modified form of the device. Fig. 3 is a further modification of the same.

The operation of the valve to open or close 30 is accomplished by pressure from the low pressure side of the same, and the valve is arranged to open a small amount as occasion requires in order to maintain a predetermined low pressure in the pipe beyond the valve. This pipe (or branch of it) is, however, 35 continued to a point where a fire extinguishing liquid may be needed, and its end closed by a fusible plug, and the design is such that upon any sudden and large reduction of pressure in the pipe, as by the 40 fusing of said plug, the main valve is opened entirely and assured of remaining open. Thus in Fig. 1 I provide in the main line 4 a valve casing 5, with a partition 6, having a valve seat 7, closed by a valve 8, which 45 opens to the outlet side 9 leading to the place where the fire extinguishing liquid may be required. The casing 5 has connected to it a chamber 10 with a flexible diaphragm 11 attached to the stem 12 of the main valve 8. 50 By means of a port (13) and passage (14)

and small port (15) governed by a ball check 16, the pressure on the low side of the main valve is introduced into the operating chamber (M) above the diaphragm 11. It will be seen that the fluid can only flow at 55 a slow rate through this restricted port (15), and that in any case upon a sudden upward rush of great pressure from port (13), on opening the valve 8, the ball check 16 will close the port (15). Connected to the chamber (M) I attach a small pipe 17 having its outlet to the air closed by the plug valve 18, which is normally held firmly to its seat by a pivoted arm 19, and a trigger 20. The trigger 20 stands in the path of an adjustable 60 nut or lug 21 on the top of the valve stem 12. A bracket 22 fixed on the main casing 5 in the usual manner carries the usual hand operating screw 23 for manually closing the valve when desired. 65

Supposing the left hand end of the main line 9 to be stopped by a fusible plug, it will be seen that a small pressure, governed by the proportional areas of the valve 8 and the diaphragm 11, will be maintained in the 70 line by feeding the chamber (M) with fluid through the ports (13), (14), (15), and the valve 8 will be closed except when this small amount of pressure is reduced by leakage or otherwise. When the fusible plug gives way 75 in the line 9, reducing the pressure therein to a very low point, the fluid in the chamber (M) may return by the port (15), and relieve the pressure above the diaphragm 11; whereupon the main valve will rise fully, eventually covering up the port (15), and the nut 80 21 will strike and trip the trigger 20, releasing lever 19 and valve 18, and therefore relieving the chamber (M) completely, and making it impossible for an accumulation of 85 pressure through port (15) upon filling the line to reestablish pressure in the chamber (M) and again close the valve. This not only because the port (15) is smaller than the pipe 17, but when the stem 12 rises fully the port 90 (15) is covered, cutting off communication with the chamber (M). In Fig. 2 I have shown a modification in which I dispense with the small escapement pipe 17 in Fig. 1, and the extra relief valve operated by the 95 100

valve stem; and in place of these I arrange on the top of the diaphragm casing 10 a supplementary air chamber 24 having a frangible glass top 25 standing immediately 5 above the valve stem 12 and below the hand operating screw 23 in the top of the bracket 20. The chamber 24 is of course entirely sealed at the top, and at the bottom communicates with diaphragm chamber (M), 10 and it will be observed that upon a sudden reduction of pressure in the line 9, as by the destruction of the fusible plug or otherwise the pressure in chamber (M) will escape by the ports 15, 14, 13, and the main valve and 15 its stem 12 will rise and break the glass plate 25, thus establishing free communication between the chamber (M) and the atmosphere. The ball check 16 will as before close the port (15) to prevent escapement 20 from the pipe line after pressure is established in the pipe 9.

In Fig. 3 I have shown another modification, in which the structure is substantially the same as Fig. 1, with the exception 25 that the pipe 17^a, carrying the escape valve 18^a, lever 19^a, and trigger 20^a, are so placed that the trigger 20^a may be tripped by the movement of lever 26 fixed on the spindle 27 of a butterfly valve 28 in the pipe line 9. 30 This is operated by the sudden rush of pressure when the main valve 8 is opened, as will be understood without further description.

By each of these devices I arrange for 35 operating the valve by the pressure on the outlet side, which, among other advantages, has the advantage of constantly testing the line and the fusible plug, of using less pressure, and of lessening the leakage. When 40 the valve once opens it is by very simple means assured of opening fully and prevented from any possibility of closing again. The structure is simple and contains nothing to get out of order. Other advantages will 45 readily occur to those familiar with the art.

Having thus described my invention and illustrated its use, what I claim is the following:—

1. A combined pressure reducing and 50 emergency valve comprising a casing with a partition having a valve seat therein, a valve having a hollow stem communicating with the delivery side of the valve, a supplementary chamber having a movable pressure 55 diaphragm of greater area than the main valve, with the chamber above it in communication with said hollow valve stem, a small valve between the hollow stem and said chamber adapted to prevent a sudden and 60 large flow of fluid therethrough, and means to establish communication between the diaphragm chamber and the outside air when the main valve opens a material distance, substantially as described.

2. An automatic fire service valve comprising 65 a casing, a main valve therein, a pressure chamber communicating with the delivery side of the valve casing, a movable wall in said chamber, a connection between said wall and valve, a normally closed passage 70 from the pressure chamber to the outer atmosphere and means operated by excessive movement of the connection between the wall and the valve to open said passage and relieve the pressure chamber.

3. A fire service valve comprising a casing, a main valve, a pressure diaphragm connected with the valve stem, and a diaphragm chamber normally maintained at a reduced pressure from the outlet side of the valve, 80 but provided with a valved port adapted to permit only a small flow of fluid toward said chamber, and to exhaust said chamber when the low pressure side of the main valve loses its pressure, a pipe connecting 85 said chamber with the outside air and closed by a valve having a device adapted to coöperate with the main valve stem to establish communication between said chamber and the outside air.

4. The combination with a pipe line having a fluid supply on one side, and a closed pipe on the other, with a fusible plug therein, of a combined emergency and reducing valve comprising a main valve, a supplemental 90 chamber with a pressure diaphragm attached to the main valve stem, a valved port connecting the low pressure side of the main valve with the top side of said pressure diaphragm chamber, and means operated by any 100 sudden and considerable opening of the main valve to completely exhaust the pressure in said diaphragm chamber, substantially as described.

5. A combined reducing valve and emergency valve comprising a casing having a perforated partition and a supplementary chamber, a valve closing the perforation of the partition mounted on a stem carrying a movable wall dividing said supplementary 110 chamber, suitable ports and passages connecting the delivery side of the casing with one of the sub-divisions of said supplementary chamber, and a valve operating to permit small and gradual flow into and out of said 115 chamber but preventing large and sudden flow into the chamber, whereby the reducing valve may be opened entirely by a sudden reduction of pressure on the outlet side, and having been opened interrupts communication 120 between the outlet side and said chamber, substantially as described.

6. An emergency valve comprising a casing with a perforated partition carrying a valve seat, a supplementary chamber of 125 greater area than said valve seat, a main valve having a hollow stem communicating with the delivery side of the casing, a mov-

able wall on said stem and completely dividing said supplementary chamber, a port connecting said stem with the supplemental chamber, and a pilot valve mounted therein
5 to seat in the direction of the chamber, but only upon sudden rush of fluid therethrough, and a normally closed outlet port

from said chamber to the atmosphere, and means on the valve stem to open said outlet port when the stem has risen beyond a pre-
determined and adjustable limit.

In testimony whereof I have hereunder signed my name.

EDWARD V. ANDERSON.
